UNITED STATES PATENT OFFICE.

LAWRENCE F. BAASH, OF FILLMORE, CALIFORNIA.

CASING-PERFORATOR.

1,272,597.

Specification of Letters Patent. Patented July 16, 1918.

Application filed September 13, 1917. Serial No. 191,325.

To all whom it may concern:

Be it known that I, LAWRENCE F. BAASH, a citizen of the United States, residing at Fillmore, in the county of Ventura and

5 State of California, have invented new and useful Improvements in Casing-Perforators, of which the following is a specification.

10 My object is to make a cutter wheel for use in casing perforators, which will cut a U-shaped slit and press the metal outwardly so as to make a shed over the hole and prevent sand, gravel and the like, which may be passing down outside of the casing, from entering the hole.

15 With the exception of the cutter wheel, the casing perforator herein shown and described is the same as that shown, described and claimed in my companion application for casing perforators, filed September 26,

20 1916, Serial No. 122,241.

Figure 1 is a side elevation of my casing perforator provided with my new cutter wheels, as seen looking in the direction indicated by the arrow —1— in Fig. 2.

25 Fig. 2 is a side elevation at right angles to Fig. 1 as indicated by the arrow —2— in Fig. 1.

Fig. 3 is a side elevation of the lower end of the casing perforator and from the opposite side of Fig. 1, as indicated by the arrow —3— in Fig. 2.

30 Fig. 4 is an enlarged sectional detail on the lines 4—4 of Figs. 1 and 3.

Fig. 5 is a fragmentary sectional detail 35 showing the cutter wheel in the operation of perforating a casing.

Fig. 6 is an edge view of the cutter wheel shown in Fig. 5, with a modified form of hub.

40 Fig. 7 is a side elevation of a modified form of cutter wheel, the wheel shown in Fig. 5 having one cutting tooth and the wheel shown in Fig. 7 having two cutting teeth, there being spacing or bearing teeth between the cutting teeth.

45 Fig. 8 is a second modified form of the cutter wheel showing five cutting teeth and no spacing or bearing teeth.

Fig. 9 is a fragmentary side elevation of 50 the casing, as seen looking in the direction indicated by the arrow —9— in Fig. 5, and showing the U-shaped slit cut in the casing.

Fig. 10 is an enlarged horizontal sectional detail on the line 10—10 of Fig. 1.

55 The casing perforator body 10 is substantially cylindrical in cross-section and is of

considerable length and has an operating shank 11 at its upper end, said shank having the usual screw-threaded pin, and has flat sides 12 for the reception of operating tools. 60 That portion of the perforator body extending below the shank 11 has a pair of longitudinally alined cutter slots 14 and 15 extending diametrically through the body, and the cutter wheels 16 and 17 are mounted in 65 these slots and are provided with spindles 18 and 19 extending into angular slots 20 and 21 formed through the body member at right angles to the slots 14 and 15. Opposite parallel faces 22 and 23 of the cutter body 70 are flat along the portion through which the slots 20 and 21 pass. The angular slots 20 and 21 are formed with the angular or inclined portions extending in opposite direction and guides 24 are formed on corresponding sides of the flat faces 22 and on opposite corresponding sides of the faces 23, as shown in Fig. 1. Slide plates 25 and 26 are formed integral, one set for each side of the machine, and these plates fit slidingly 75 upon the flat faces 22 and 23 and have transverse slots 27 in which the spindles 18 and 19 of the cutter wheels 16 and 17 are mounted. Longitudinally extending leaf springs 28 and 29 are placed against the outer faces 80 of the two sets of slide plates 25 and 26, and a bolt 30 is inserted through the upper ends of these springs and through the slots 20 to hold the springs and plates together. A bolt 31 is inserted through the lower ends 85 of the springs 28 and 29 and through the slide plates and through the slots 21, thus holding the lower ends of the slide plates together.

In Fig. 1 the upper guide 24 is at the right- 95 hand side of the flat face 22 and the lower guide 24 is at the left-hand side of the flat face 23, and the spindle 18 of the cutter wheel 16 moves to the left while the spindle 19 of the cutter wheel 17 moves to the right 100 when the body 10 is lowered relative to the perforating mechanism.

A lock pin 32 is mounted within a transverse bore 33 formed horizontally through the lower end of the body member and parallel with the bolt 31. The pin 32 is formed with a head 34 and has a pair of oppositely disposed transverse slots 35 adjacent its other end. These slots form a reduced neck like a button adapted to engage in a lock 110 slot 36 formed through the lower end of one of the slide plates 26 and this slot 36 has

an enlarged opening at its upper end for permitting the free passage of the pin 32 so as to allow the neck 35 to register with the main portion of the slot. The pin 32 is normally drawn within its recess by a coil spring 37 acting beneath its head to positively insure the release of the cutting wheel operating mechanism when desired.

When the casing perforator is to be lowered into a well casing, a tool is inserted through an opening 34 in the opposite slide plate 26 from the slot 36 to press the pin 32 outwardly to engage in the slot 36 and lock the cutter wheels in their withdrawn position. Ball bearings 38 are applied to the circular surface of the body 10 to make the body move freely up and down in the well casing.

The cutter wheels 16 and 17 are identical, the cutter 16 being set to project from the left-hand side of the tool in Fig. 1 and the cutter 17 being set to project from the right-hand side, and in Figs. 5 and 6 I have shown the cutter 17.

The cutter 17 is preferably forged from tool steel and comprises a hub 39 or 39' having a central opening 40 to receive the spindle 19; an annular body portion 41 extending from the hub and thinner than the hub; a cutter tooth 42 extending from the body 41; and the bearing teeth 43 extending from the body 41 in a series from one side of the tooth 42 around to the other side. The cutter tooth 42 has a straight rear face 44 radial to the axis of the wheel, and a rounded inclined face 45 leaving tangentially an inner circle of the wheel and meeting the outer end of the straight face 44 to form the transverse cutting edge 46. The curvature of the face 45, when continued as indicated by the line —c— in Figs. 5, 7 and 8, is substantially half way between the center of the wheel and the periphery of the bearing teeth, and the edge 46 is the only transverse cutting edge. The inclined face 45 extends inwardly beyond the cutting depth, that is, the depth to which the tooth will perforate a casing. The cutting edges are formed upon the tooth along the sides of the straight face 44 and extending inwardly from the cutting edge 46, and the cutting edges 47 and 48 are formed along the sides of the inclined face 45 and extending inwardly from the transverse cutting edge 46, so as to cut a U-shaped slit in a casing, said slit comprising the line 49 cut by the edge 46, and the lines 50 and 51 cut by the edges 47 and 48. The bearing teeth 43 are regularly spaced and are A-shaped in side elevation, the points 52 of the bearing teeth being in a concentric line and said line crossing the face 44 of the tooth 42 substantially at its center. In other words, the tooth 42 extends half its length beyond the concentric plane of the teeth 43. The points

52 of the teeth 43 bear against the inner face of the casing 53 with considerable pressure so as to rotate the cutter wheel in the direction of the arrows —b— in Figs. 5, 7 and 8, and bring the tooth 42 into action. The perforating is done upon the downward movement of the tool relative to the casing as indicated by the arrows —a— in Figs. 5, 7 and 8 and the spacing teeth 43 rotate the cutter until the edges 47 and 48 and the point 46 strike the casing, and continued movement of the tool downwardly forces the transverse cutting edge 46 through the casing and continued downward movement of the tool again brings the bearing teeth 43 into operation and withdraws the cutter tooth 42 from the perforation. The perforation thus formed cuts the metal on three sides, 49, 50 and 51, and leaves the shed 54 hanging at the top so as to extend outwardly and downwardly and cover the perforation.

In the modification shown in Fig. 7 I have shown two cutting teeth 55 and 56 substantially like the tooth 42 and arranged diametrically opposite each other with the bearing teeth 57 and 58 occupying the remainder of the circumference of the wheel. Of course, this cutter will make two perforations to a revolution and the perforations will be closer together.

In the modification shown in Fig. 8 I have shown a cutter wheel having cutting teeth 59, 60, 61, 62 and 63 evenly spaced apart and occupying the entire periphery of the wheel so that no bearing teeth are needed. This cutter wheel will make five perforations at one revolution and the perforations will be comparatively close together. The rounded sides of the cutting teeth may have transverse serrations 64. These serrations are or may be like a file with their edges pointed toward the transverse cutting edge 46 so that the file edges 64 will grip the side of the casing and assist in rotating the cutter wheel to bring the transverse cutting edge 46 into operation.

In the operation of the casing perforator, the tool is set as shown in Figs. 1, 2 and 3, the cutter wheels 16 and 17 being withdrawn into the body of the tool and held in their withdrawn position by forcing the pin 32 outwardly so that the neck formed by the recesses 35 will pass downwardly in the slot 36. During this operation, the spindles 18 and 19 are in the straight portions of the slots 20 and 21 and the pin 32 passing to the bottom of the slot 36 holds the slide plates from going upwardly to carry the spindles 18 and 19 into the angular portions of the slots 20 and 21. The tool is then inserted into the casing and the springs 28 and 29 bear against the inner face of the casing with considerable force. When the tool has reached the proper depth in the casing the perforator body is drawn upwardly and the

springs 28 and 29 engaging the casing will hold the slide plates 25 and 26 stationary in the casing until the pin 32 reaches the head of the slot 36 and then the tension of the 5 spring 37 will withdraw the pin and leave the slide plates free to operate upon the body 10. Then the perforator body is lowered and the slide plates being held stationary in the casing the spindles 18 and 19 10 will pass upwardly into the angular portions of the slots 20 and 21 and carry the cutter wheels outwardly into operating position. Further lowering of the tool will cause the 15 cutting teeth to engage the casing and form perforations. Moving the tool upwardly will withdraw the cutters and the tool can be rotated or raised or lowered as desired.

The shed over the perforation is very desirable, as it will prevent sand, gravel, and 20 the like which is passing downwardly outside of the casing, from passing through the perforation into the casing.

While my new cutter is especially adapted for use in the tool shown and described, various changes may be made in the tool or a 25 different style of tool may be used, and various forms of the cutter may be used, without departing from the spirit of my invention as set up in the following claims:

30 I claim:

1. A cutter for casing perforators, comprising a wheel, and a cutting tooth projecting from the periphery of the wheel; said cutting tooth having a straight rear 35 face radial to the axis of the wheel and a rounded inclined face leaving tangentially an inner circle of the wheel and meeting the outer end of the straight face to form a transverse cutting edge.

40 2. A cutter for casing perforators, comprising a wheel, bearing teeth projecting peripherally from the wheel, and a cutting tooth projecting from the periphery of the wheel; one side of the cutting tooth being 45 a straight rear face radial to the axis of the wheel and the opposite side of the cutting tooth being a rounded inclined face leaving tangentially an inner circle of the wheel and meeting the outer end of the straight face 50 to form a transverse cutting edge.

50 3. A cutter for casing perforators, comprising a wheel, bearing teeth projecting peripherally from the wheel, and a cutting

tooth projecting from the periphery of the wheel; one side of the cutting tooth being a 55 straight rear face radial to the axis of the wheel and the opposite side of the cutting tooth being a rounded inclined face leaving tangentially an inner circle of the wheel and meeting the outer end of the straight face 60 to form a transverse cutting edge, and there being means upon the rounded face for gripping the casing to rotate the wheel.

4. In a casing perforator, a body member having upper flattened faces at opposite 65 sides and lower flattened faces at opposite sides, said upper and lower faces being offset relatively to each other and there being guides along corresponding sides of the upper faces and guides along corresponding 70 sides of the lower faces, the upper guides being at opposite sides of the faces from the lower guides, and there being a longitudinal slot extending through the body at right angles to the faces and each pair of faces 75 being provided with a transverse slot at right angles to the longitudinal slot, the lower portions of said transverse slots being longitudinal and the upper portions of said slots being oppositely inclined, slide 80 plates mounted on the flattened faces and against the guides and having cutter wheel bearings transversely elongated, cutter wheels in the longitudinal slot and having spindles extending into the elongated cutter 85 wheel bearings; so that as the slide plates move upwardly relatively to the body the cutter wheels will move laterally and project their teeth beyond the body; cutting teeth upon the cutter wheels; said teeth projecting from the peripheries of the wheels and said cutting teeth each having a straight rear face radial to the axis of the wheel and a rounded inclined face leaving tangentially 90 an inner circle of the wheel and meeting the outer end of the straight face to form a transverse cutting edge; means for holding the slide plates in position to withdraw the cutter wheels while the perforator is being pushed downwardly into a casing, and 95 means to cause the slide plates to stick in the casing and force the cutter wheels outwardly to perforate the casing.

In testimony whereof I have signed my name to this specification.

LAWRENCE F. BAASH.
